UNITED STATES PATENT OFFICE.

JOSEPH E. PERRAULT, OF BELMONT, MASSACHUSETTS, ASSIGNOR TO HOOD RUBBER CO., OF WATERTOWN, MASSACHUSETTS, A CORPORATION OF MASSACHUSETTS.

METHOD OF AND MACHINE FOR FOLDING THE EDGES OF RUBBER SHEETS.

1,111,232.

Specification of Letters Patent. Patented Sept. 22, 1914.

Application filed February 3, 1914. Serial No. 816,315.

To all whom it may concern:

Be it known that I, JOSEPH E. PERRAULT, a citizen of the United States, residing at Belmont, Massachusetts, have invented certain new and useful Improvements in Methods of and Machines for Folding the Edges of Rubber Sheets, of which the following is a specification.

My invention relates to improvements in method of and means for folding the edges of stock or material such as used more especially in the manufacture of rubber goods and shoes. In the manufacture of articles of this character a fabric is used which is provided with a facing or coating of rubber applied by means of a calender, and as the coated strip of fabric comes from the calender there is a strip or edge of the unvulcanized rubber which projects beyond the fabric. This must be folded over upon the inner face of the fabric, and as the edge of the fabric strip is of irregular contour, and the rubber unvulcanized and hence of sticky character, this folding operation is one of some difficulty and has heretofore, so far as I am aware, only been done by hand.

The object of the present invention, therefore, is to provide a method and a mechanical device or apparatus for accomplishing this folding action in a simple and expeditious manner, and the invention includes the novel construction hereinafter described and particularly pointed out in the appended claims.

35 A form of mechanism embodying my invention is illustrated in the accompanying drawing, in which—

Figure 1 is a plan view; Fig. 2 is an end elevation; Fig. 3 is a side elevation; Fig. 4 is a detail view of a sample of stock with the edge partly folded, and Fig. 5 is a detail view.

Referring by reference characters to this drawing, the numeral 1 designates a suitable bed plate or frame designed to be adapted to any convenient support, and having journaled between upwardly extending bearing lugs 2 a roller 3 over which the edge of the stock to be folded is adapted to be moved. The stock, which is indicated at A, is held and passed over the roller by hand, the edge to be folded over by the machine being indicated at a. As the stock is moved along over the roller 3 in the direction of the arrow X in Fig. 1, the project-

ing edge of the soft rubber is thrown upward by the action of the rapidly rotating folding disk or wheel 4, which is provided with a plain, smooth edge and driven in any suitable manner, as, for instance, by a belt 60 passing over a grooved or pulley portion 4^a which is conveniently formed integral with the disk or wheel 4. This wheel 4 is journaled on a stud projecting from the carrying bracket 5. The rotation of the disk 65 or wheel 4 causes the soft rubber as it comes in contact with the edge of the disk to be thrown upward over and back upon the inner face of the fabric, and it is then pressed down so as to cause it to adhere smoothly to 70 the inner face of the fabric by the presser or hammer 6. This presser device has a downwardly extending or elbow portion 6^a journaled upon the pin or stud 7, and to the angle or elbow 6^b is pivotally connected by 75 pin 7' the end of a rod or pitman 8, the other end of which is eccentrically connected to an operating shaft 9. I prefer to make this eccentric connection in the shape of a strap 10 encircling an eccentric 13 carried 80 by the shaft, with preferably a circular series of balls between the strap and eccentric, as shown, and I also prefer to journal the shaft 9 in ball bearings, as shown, and drive the same from a pulley 11, though it will be 85 understood, of course, that I do not limit myself to this particular form of driving means.

Having thus described my invention what I claim is:—

1. In combination a movable support for the stock to be folded, a rotary disk having its edge located in proximity to said support, and arranged to rotate in a plane substantially perpendicular to the edge of the 95 stock, and a presser device moving toward and from the face of said support.

2. In combination a roller support, a rotary folding disk having its edge in proximity to said support and journaled upon 100 an axle lying in a horizontal plane substantially tangential to the upper face of said support, a presser device or hammer adapted to press the material operated upon against said support, and means for oscillating the 105 hammer.

3. In combination a roller journaled upon a horizontal axis, a disk having a smooth edge located in proximity to the upper face of said roller, a presser device or hammer 110

projecting across the upper face of the roller, and having a depending arm pivoted upon a fixed support, a pitman pivotally connected at one end to said arm and an eccentric for operating the opposite end of said pitman, substantially as described.

4. The herein described method of folding sheets of unvulcanized or like adhesive material which consists in causing the edge 10 of the sheet to progressively contact with a

smooth edged disk or roller rotating in a plane substantially perpendicular to the edge of the sheet.

In testimony whereof, I affix my signature in presence of two witnesses.

JOSEPH E. PERRAULT.
